UNITED STATES PATENT OFFICE.

HENRY G. RODGES, OF WESTBOURNE PARK, LONDON, ENGLAND.

MACHINE FOR PARING AND FINISHING BOOTS AND SHOES.

No. 827,570.

Specification of Letters Patent.

Patented July 31, 1906.

Application filed December 20, 1904. Serial No. 237,685.

To all whom it may concern:

Be it known that I, HENRY GEORGE RODGES, shoemaker, a subject of the King of Great Britain, residing at 108 Acklam road, 5 Westbourne Park, London, England, have invented certain new and useful Improvements in Machines for Paring and Finishing Boots and Shoes, of which the following is a specification.

In the specification of British Patent No. 24,141 of 1902 is described a machine for paring and finishing boots and shoes wherein three tools are mounted in bearings on a frame arranged coaxially with a driving-shaft 10 and so as to rotate. The standard that carries the driving-shaft also carries a loose pulley in such a position that when the said frame is rotated each tool can be brought in turn into alignment with the axis of the loose 15 pulley. Thus a belt driven by a pulley on the driving-shaft can be shifted from the loose pulley onto a pulley keyed to the tool in order to drive the latter.

By my invention I mount two rotatable 20 frames on one frame or standard and the tools on these tool-frames in such a manner that two tools, one on each frame, can be driven directly by the same belt. A machine constructed in this manner is much lighter and 25 more compact for its number of tools than that described in the aforesaid specification and can be driven with less consumption of power.

In the accompanying drawings I have illustrated the preferred form of my new machine. 30 Figure 1 is a side elevation of the machine without a dust-collector, and Fig. 2 is a plan thereof with a dust-collector and having certain parts broken away. Fig. 3 is a front view of the tool-frame mounted on the machine. Fig. 4 is a side elevation; Fig. 5, a plan of a modification, and Fig. 6 is a plan of a 35 second modification.

Like letters of reference indicate like parts in all the figures.

To the top surface of a standard *a*, in bearings in which may be mounted the driving-shaft *b*, are adjustably fixed two brackets *c*, each carrying a vertical boss or disk *d*, whereon is mounted, so as to rotate, a tool-frame *e*. 40 The latter has a number of arms *f*—in this instance four—each with a bearing *g* for a tool-spindle *h*, on which spindle is fixed a pulley *i*. 45 In order that by rotating the frames two tool-spindles *g*, one on each frame, may be

brought together so that their axes are in the same straight line as shown in Figs. 1 and 2, the bosses or disks *d* or the brackets carrying them are mounted in vertical planes which are at an angle to each other, and the arms *f* are bent forward to make an angle with the said plane, 55 or the whole tool-frame may be slightly dished. This arrangement also allows the standard *a* to be of comparatively considerable dimensions without interfering with the rotation of the tool-frames. When two tool-spindles have been brought together in the manner described, their pulleys *i* register with each other and may both be driven by a belt *k*, passing over a driving-pulley, such as *l*. By means of a fork *m* the belt *k* may be 60 shifted from the position shown in Figs. 1 and 2, so as to run on either pulley *i* alone, thus leaving one of the tool-frames free to rotate without being impeded by the belt.

The direction of rotation of the tool-frame 75 is indicated by the arrow in Fig. 3, and in order to retain the frame in place when the tools are in the desired position there is pivoted in a recess in the disk *d* a spring-detent *n*, which engages in an appropriately-shaped 80 notch *o* in the tool-frame when any one of the tools is in the position for being driven by the belt.

When a dust-collector is necessary, it may 85 consist of a hood, such as *p*, carried by a suction-pipe, such as *r*, passing through the disk *d* to the suction side of a fan. (Not shown in the drawings.) When only one of the tools on a frame requires a dust-collector, the pipe *r* 90 may be mounted in a bush at the center of the disk *d*, so that it can rotate with the tool-frame, in which case it may be supported by an arm or bracket carried by the tool-frame, or the pipe *r* may be fixed and the hood *p* may be made to be opened when the tool-frame is 95 to be rotated, so that each tool when brought into operative position may be covered by closing the hood.

Although I prefer to mount the tool-frames in the manner I have described, as I believe 100 this gives the most compact and stable machine for its weight, I may mount the tool-frames *e* in parallel planes, as shown in Figs. 4 and 5. In this case the tool-spindles *h* slide in their bearings *g* and are at right 105 angles to the planes of the tool-frames. When not in use, the tool-spindles are drawn forward, as shown at the top and bottom of

Fig. 4, so that when the frames are rotated the pulleys i' clear the standards a' . When the tools are to be operated, the spindles h' are slid back until the belt k' can run on the pulleys i' .

In the modification shown in Fig. 6 the frames e^2 are mounted in planes at an angle to each other, as in the form shown in Figs. 1 and 2, but instead of bending the arms f^2 in the manner shown in Figs. 1 and 2 the bearings g^2 are mounted at an angle to these arms to insure that the two tool-spindles which are in their operative position shall have their axes in the same straight line. The standard a^2 is cut away to allow the pulleys i^2 to pass when the tool-frames are rotated.

Having thus described the nature of this invention and the best means I know of carrying the same into practical effect, I claim—

1. A machine for paring and finishing boots and shoes, comprising a standard, two tool-frames mounted on the said standard in vertical planes at an angle to each other, tool-spindles mounted in each of the said frames each of the said spindles in one frame being adapted to be brought into the same straight line with any spindle of the other frame with its rear end in close proximity to the rear end of the spindle with which it is in line and means for rotating simultaneously the two spindles in line.

2. A machine for paring and finishing boots and shoes, comprising a standard, two rotatable tool-frames mounted on the said standard in vertical planes at an angle to each other, tool-spindles mounted in each of the said frames at an angle to the plane in which the frame is mounted such that by rotating the frames two spindles one on each frame can be brought into the same straight line with their rear ends in close proximity, and means for rotating simultaneously the two spindles thus brought in line.

3. A machine for paring and finishing boots and shoes, comprising a standard, two rotatable tool-frames mounted on the said standard in vertical planes at an angle to each other, tool-spindles mounted in each of the said frames at an angle to the plane in which the frame is mounted such that by rotating the frames two spindles one on each frame can be brought into the same straight line with their rear ends in close proximity, a pulley on the rear end of each spindle, a driving-shaft, a driving-pulley on the said shaft and a belt passing over the said driving-pulley and both the pulleys of the two spindles which are in line with each other.

4. A machine for paring and finishing boots and shoes, comprising a standard, two bosses carried by the said standard, a tool-frame mounted to rotate on each of the said bosses in vertical planes at an angle to each other, tool-spindles mounted in each of the said frames, each of the said spindles in one

frame being adapted to be brought into the same straight line with any spindle of the other frame with its rear end in close proximity with the rear end of the spindle with which it is in line, means for rotating simultaneously the two spindles in line, a dust-collecting hood and a suction-pipe carrying the said hood and passing through the boss on which the said frame is mounted. 70

5. A machine for paring and finishing boots and shoes, comprising a standard, two bosses carried by the said standard, a tool-frame mounted to rotate on each of the said bosses in vertical planes at an angle to each other, tool-spindles mounted in each of the said frames, each of the said spindles in one frame being adapted to be brought into the same straight line with any spindle of the other frame with its rear end in close proximity with the rear end of the spindle with which it is in line, means for rotating simultaneously the two spindles in line, a dust-collecting hood, a suction-pipe carrying the said hood and passing through the boss on which the said frame is mounted, the said suction-pipe being adapted to rotate with the frame. 85

6. A machine for finishing boots and shoes having two sets of tool-spindles, means for supporting said spindles in a normally inclined relation to each other, said supporting means permitting the spindles to be moved to bring a spindle of one set into a straight line with a spindle of the other set, and means for rotating the alining spindles simultaneously. 95

7. A machine for finishing boots and shoes having two sets of tool-spindles, means for supporting said spindles in a normally inclined relation to each other, said supporting means permitting the spindles to be moved to bring a spindle of one set into a straight line with a spindle of the other set, means for rotating the alining spindles. 100

8. A machine for finishing boots and shoes having two shiftable sets of rotatable tool-spindles, a power-transmitting means upon the inner end of each of said spindles, means for supporting the spindles of one set out of operative alinement with the spindles of the other set, said means permitting the power-transmitting means of a spindle of one set to be brought into alinement with the power-transmitting means of a spindle of another set, and a single operating means for engaging the power-transmitting means of the alined spindles for operating them. 115

9. A machine for finishing boots and shoes having two shiftable sets of rotatable tool-spindles, a pulley upon the inner end of each of said spindles, means for supporting the spindles of one set out of operative alinement with the spindles of the other set, said means permitting the pulley of a spindle of one set to be brought into alinement with the pulley of a spindle of another set, and a single oper- 125

ating means for engaging the pulleys of the alined spindles for operating them.

10. A machine for finishing boots and shoes, having two shiftable sets of rotatable tool-
5 spindles, means for supporting the spindle of one set out of operative alinement with the spindles of the other set, said means permitting a spindle of one set to be brought into alinement with the spindle of another set,

and a single operating means for engaging 10 with the alined spindles for operating them.

In testimony whereof I have signed my name to this specification in the presence of two subscribing witnesses.

HENRY G. RODGES.
